(57) **CLAIM**

The ornamental design for a double tip-double sided carpenter's tape measure, as shown.

DESCRIPTION

FIG. 1 is a side view of a double tip-double sided carpenter's tape measure showing our new design, with the tape engaged;

FIG. 2 is a side view, with the tape retracted;

FIG. 3 is a top plan view; and,

FIG. 4 is a bottom plan view thereof.
